UNITED STATES PATENT OFFICE.

CHARLES A. BOYER, OF WAREAW, INDIANA, ASSIGNOR TO HUGRO MANUFACTURING COMPANY, OF CHICAGO, ILLINOIS, A CORPORATION OF ILLINOIS.

CARPET-SWEEPER.

1,169,526.

Specification of Letters Patent. Patented Jan. 25, 1916.

Application filed November 13, 1914. Serial No. 871,912.

To all whom it may concern:

Be it known that I, CHARLES A. BOYER, a citizen of the United States of America, and resident of Warsaw, Kosciusko county, Indiana, have invented a certain new and useful Improvement in Carpet-Sweepers, of which the following is a specification.

One of the objects of my invention is to provide an improved machine of this character which will be simple, durable and reliable in construction, and effective and efficient in operation.

Other objects of my invention will appear hereinafter.

15 My invention consists in the features of novelty exemplified in the construction, combination and arrangement of parts shown in the accompanying drawings, described in the following specification, and 20 more particularly set forth in the appended claims.

Referring to the drawings—Figure 1 is a top plan view of an improved machine embodying my invention. Fig. 2 is a view in 25 elevation of one side of the machine shown in Fig. 1. Fig. 3 is a view in elevation of the opposite side of said machine. Fig. 4 is a longitudinal vertical section substantially on the line 4—4 of Fig. 1. Fig. 5 is a view 30 in front elevation of the machine, showing the intake nozzle swung downwardly or opened to disclose the interior of the forward end of the machine. Fig. 6 is a sectional view on the line 6—6 of Fig. 5. Fig. 35 7 is a face view of the inner side of the nozzle, showing the sealing gasket. Fig. 8 is a sectional view of a portion of the rear end of the machine, showing the dust pans and their operating parts; and Fig. 9 is a detail 40 section substantially on the line 9—9 of Fig. 1.

In the drawings, I have shown my invention as embodied in the structure which I have found best adapted to requirements 45 and conditions, but it will be obvious to one skilled in the art, after having obtained an understanding of my invention from the disclosures herein made, that my invention is capable of modification and rearrangement without departing from the scope and 50 spirit of the invention, and I wish it so understood.

The body structure of the machine shown 55 in the drawings involves a frame on which the various operating parts are mounted.

This frame in the present structure is preferably in the form of a housing or casing A which is preferably made up of sheet metal on account of the cost and convenience of construction. The rear end of the structure is supported by a pair of wheels 1 which are mounted upon a transverse shaft 2 suitably journaled in bearings formed in the frame or casing. This transverse shaft has a plurality of crank portions 3, which through the medium of the connecting rods or links 4 actuate the bellows or pumpers 5, the power being applied to the cranks through the tractive effect of the wheels 1 upon the floor or surface over which the 70 device is propelled.

The connecting links 4 are pivotally connected to extensions 6 on the movable elements or members 7 of the pumpers. The fixed or lower elements of the pumpers are 75 mounted upon and supported by a transverse partition wall 8 substantially midway of the height of the body structure and extending almost to the rear end of the casing, leaving just sufficient room for the operation 80 of the bellows-operating cranks. At this point the partition wall extends downwardly to protect the bottom of the casing where it forms a shoulder 10, the purpose of which 85 will later appear. At the forward end the bellows or pumpers have a plurality of valved holes or openings 11 which communicate with a vacuum compartment 12. This compartment is formed by the side walls of the casing and the forward portion of the partition 8, together with another and lower 90 horizontal partition 13 and a vertical wall or partition 14, the latter closing the rear end of the compartment 12. The forward end of the compartment is open and substantially flush with the forward end of the 95 casing. The compartment 12 is occupied by a removable dust collector device C, and across the forward end of the casing is positioned the usual dust intake nozzle D.

On the under side of the body structure are two dust pans or trays 45 and 46, which are arranged to receive the dust and other articles which are picked up by the rotary brush 47. These dust pans extend transversely substantially the entire width of the casing and are formed in transverse section substantially as shown in Figs. 4 and 8. They are open at their upper sides and have 105 inner vertical walls 48 adjacent the brush. 110

These pans are spaced apart to sufficiently accommodate the rotary brush between them. They are pivoted at the points 49 at each end to the side walls of the casing, so that they may be tilted or swung downward into substantially vertical planes for the purpose of dumping them. The outer edge portion of the dust pan 45 bears, when in normal position, against the under side of the compartment wall 13, as shown clearly in Figs. 4 and 8. This restricts its upward movement and holds it in definite position with respect to the rotary brush. The other pan 46 is correspondingly positioned and its outer edge portion, like that of the pan 45, coöperates with the offset shoulder 10 in the partition wall of the casing, as previously explained. Adjacent one side of the casing and at corresponding ends of the two pans is a single link or lever member E common to both pans. This operating link is pivoted intermediate its ends to the pan 46 at the point 50 on one side of the pivotal point of said pan 45. One end of said lever E is pivoted at the point 51 on the other pan 45, the point 51 being on a corresponding side of the pivotal point 49 of said pan 45. The other end or arm of the lever extends rearwardly to a point where it projects beyond or at least substantially even with the rear end of the casing and is formed as a finger-piece 52. Thus by depressing the finger-piece 52 of the operating link both pans may be simultaneously swung downward for the purpose of dumping their contents. A spring 53 fastened to the casing and to the lever E adjacent its finger-piece operates to pull upwardly on the operating link E and thus maintain the pans in their normal or closed positions. I am thus enabled by this construction to employ a single operating member for the pans having direct pivotal connection with and common to both of the pans, thus reducing the expense of manufacture and providing an extremely simple operating mechanism.

It will be observed also that an important advantage is obtained by arranging the dumping lever to lie underneath the casing approximately parallel with the floor line and having its operating end extending to the rear of the machine, where it may be conveniently operated by the foot of the operator. This arrangement of the dumping lever is simple and durable and, furthermore, avoids the necessity of extending it up to the top of the casing.

The rotary brush 47, as clearly shown in the drawings, is mounted upon a shaft 60 which carries at its ends frictional driving rollers or gears 61. These frictional members coöperate with a pair of auxiliary or intermediate tractor wheels 62, which, as shown in the drawings, are positioned intermediate the ends of the casing or body

structure and on the side of the brush opposite that of the supporting wheels. These wheels are mounted upon a shaft 63 so that they will rotate in unison, but the shaft passes through comparatively large openings 64 in the side walls of the casing so that said shaft and its wheels may have considerable relative movement with respect to the casing. The ends of the shafts project into openings 65, which, as shown clearly in Figs. 2 and 3, are formed in bridge or stirrup members 66 rigidly secured at their ends to the casing. These bridge members occupy positions outside of the intermediate wheels and the frictional members of the brush, so as to protect these members from becoming damaged during the operation of the machine. The opening 65 is formed by offsetting or striking a small tongue from the body of the straps 66, and said opening confines the movement of the wheels within certain limits so as to prevent undue displacement of said wheels with respect to the body.

The intermediate wheels 62 are yieldingly pressed into contact with the floor by means of spring 67, which, as shown clearly in Fig. 4, are fastened at 68 to the horizontal partition wall 8 of the casing and the free end of which bear upon the shaft 63. These springs are disposed in such manner that they yieldingly press the wheels downwardly against the floor as well as toward the friction wheels of the rotary brush.

In a structure of this character, it is desirable not only to be able to connect and disconnect the brush with respect to the driving wheels, but also to adjust the brush relatively to the surface to be cleaned, in accordance with the particular requirements under which the machine is operating. I, therefore, mount the brush shaft in the ends of two levers 70. These levers, as shown clearly in Figs. 1 and 9, occupy a position just inside of the bridge members or stirrups 66, and they are pivoted to these stirrups by means of the rivets or bolts 71. The levers also have slots 72 in them so as to provide a sort of lost motion or pin and slot connection which allows the levers not only to be swung on their pivots but also to be shifted longitudinally. At their other ends the levers 70 carry small disk-shaped members 73 which are rotatably mounted in openings in said levers. A rod or shaft 74, common to both of said levers, is fixed in these rotary members 73, but it will be noted, as seen in Fig. 9, that the rod is eccentric with respect to the center of rotation of said members 73. The rod itself, however, is journaled in bearings in the stirrups or straps 66. Hence any rotation of the rod operates the member 73 and causes the levers to not only rock about their pivots 71 but also to move longitudinally, depending upon the amount which the rod is rotated. The operation of this rod thus

causes the levers 70 not only to raise and lower the rotary brush with respect to the floor, but also to bodily shift the brush to and from driving relation with the wheels 62. The springs 67 will, of course, maintain the intermediate wheels against the friction members 61 of the brush through a certain range of rotation of the operating shaft 74. During this range of operation the brush is 10 operated up and down relatively to the floor. Beyond this range the eccentric members 73 operate to withdraw the brush from engagement with the intermediate wheels 62. This withdrawal of the brush is arranged for by 15 limiting the distance which the wheels may move in following the brush, this limitation being accomplished by the openings 65 in the stirrup members 66. At one side of the structure, as shown clearly in Fig. 1, the end 75 20 of the shaft may be turned to form an operating handle, and limit stops 76 may be formed on the stirrup members to limit the range of rotation of the shaft by coöperation with the handle members 75. Comparatively large 25 openings 77 are provided in the side walls of the casing to allow for this bodily movement of the brush. This construction permits a universal adjustment of the brush which may be made with great accuracy. A suitable 30 handle 80 is provided for manipulating the machine. This handle has a bail 81 at its lower end which is pivoted at 82 to the sides of the casing, and which engages with clips 83 for holding the handle in an upright position when the operator's hands are released 35 from it.

What I claim as my invention is:

1. In a carpet sweeper, the combination of a casing and means for supporting it as it is moved to and fro on the carpet, bridge plates fastened to the opposite sides of said casing, a shaft journaled in said plates and extending through the casing and provided at its ends with drive wheels, a transverse 40 brush carrying friction wheels at its ends adapted to engage with the aforesaid drive wheels, a pair of levers pivotally mounted on said bridge plates and having the shaft of the aforesaid brush journaled in their 45 forward ends, means mounted on the casing for simultaneously raising and lowering the rear ends of said levers to thus raise and lower the brush, and means for resiliently pressing the drive wheels toward the floor 50 and the friction wheels on the brush shaft so that when the brush is in its lowered position it will be driven by said drive wheels.
  2. The combination of a body structure, wheels yieldably mounted thereon, a rotary 55 brush, a lever supporting the brush, and means for actuating said lever to bodily shift the brush into and out of driving relation to said wheels and toward and from the floor.
  3. The combination of a frame, wheels 60
- mounted thereon, a rotary brush having wheel-engaging means by which it is rotated, a pair of levers pivotally mounted on said frame and supporting said brush at one end, a transverse shaft, and means thereon 70 for actuating said levers to shift the brush relatively to the floor and into and out of driving relation to said wheels.
4. The combination of a casing, a pair of wheels yieldably mounted thereon for contact with the floor, a rotary brush disposed on an axis parallel with the wheel axes and having rollers at its ends for frictional driving connection with said wheels, a lever pivotally mounted on the casing adjacent each end of the brush and supporting the brush at one of its ends, a transverse shaft common to and having an eccentric connection with the other ends of said levers for 75 rocking the levers to adjust the brush.
5. In a carpet sweeper, the combination of a casing mounted on traction wheels, a brush extending transversely of the casing and driven from said wheels, a tray pivotally supported at each side of the brush and within the casing, and a lever for simultaneously dumping the trays, said lever being pivotally connected to both trays and extending backwardly underneath the casing, its rear end being accessible for depression by the 80 operator.
6. In a carpet sweeper, the combination of a casing mounted on traction wheels, a brush extending transversely of the casing and driven from said wheels, a tray pivotally supported at each side of the brush and within the casing, a lever for simultaneously dumping the trays, said lever being pivotally connected to both trays and extending backwardly underneath the casing, its rear end being accessible for depression by the 85 operator, and a spring connecting said lever to the casing and acting to normally raise the lever and the trays.
7. In a carpet sweeper, the combination of a casing carrying means for supporting the same at its forward end as well as its rear end as the casing is moved to and fro over the carpet, transverse dumping pans within the casing, a transverse brush journaled 90 within the casing and provided with friction wheels at its ends, a pair of floor-engaging drive wheels affixed to a shaft extending transversely of the casing, means for resiliently pressing this shaft with its 95 wheels toward the floor as well as toward the brush shaft, and means for raising and lowering the brush and moving it toward and from said drive wheels, whereby when the brush is lowered its friction wheels will engage the drive wheels and when raised will be out of contact therewith.
8. In a carpet sweeper, the combination of a casing and means for supporting the same as it is moved to and fro over the carpet, a 100

transverse rotary brush carrying friction wheels, means whereby this brush and its friction wheels are bodily moved upwardly and downwardly as well as forwardly and backwardly, a transverse shaft parallel with the brush shaft and carrying floor-engaging driving wheels, this shaft being supported in such manner as to have free bodily movement toward and from the floor and also 10 toward and from the brush-driving wheels,

and means for resiliently pressing this shaft and its wheels toward the floor and also toward the brush-driving wheels.

Signed by me at Warsaw, Ind., this 2nd day of Nov. 1914.

CHARLES A. BOYER.
